UNITED STATES PATENT OFFICE.

HERBERT M. STURGIS, OF SOUTH CHARLESTON, OHIO.

CAR-COUPING.

SPECIFICATION forming part of Letters Patent No. 300,030, dated June 10, 1884.

Application filed April 24, 1884. (No model.)

To all whom it may concern:

Be it known that I, HERBERT M. STURGIS, a citizen of the United States, residing at South Charleston, in the county of Clark and 5 State of Ohio, have invented a new and useful Automatic Car-Coupling, of which the following is a specification, reference being had to the accompanying drawings.

My invention relates to car-couplings; and 10 it has for its object to provide a device of this character for automatically coupling the cars which shall be simple in its construction and operation and durable in its use.

A further object of the invention is to provide a coupling whereby cars of different 15 heights may be readily coupled without any necessity of adjustment of the parts.

With these ends in view the invention consists in the improved construction and combinations of parts, hereinafter fully described, 20 and pointed out in the claims.

In the drawings, Figure 1 is a perspective view of a car-coupling constructed in accordance with my invention. Fig. 2 is a longitudinal section of the same, showing the cars 25 coupled; and Fig. 3 is a transverse section.

Fig. 4 is a detached view of the latch or hook.

In the accompanying drawings, in which like letters refer to corresponding parts in the 30 several figures, A represents a draw-head, which is divided for about half its length, forming an upper and a lower portion, a', the front ends of which are beveled both upon their upper and lower sides, as shown. The 35 upper and lower portions, a and a', are provided with a vertical slot, b, of different diameters, said slot b extending rearwardly into the draw-head. Within this slotted portion of the draw-head is pivoted the coupling latch 40 or hook, which consists of a body portion, d, having the two arms e, provided at their forward ends with depending hooks e'. Upon the upper side of the coupling hook or latch is provided a bail, f, to which is loosely attached a loop of a double lever, E. This lever 45 is provided at its ends with downwardly-extending handles, and is pivoted on the upper side of the draw-head by means of staples g. A chain may also be attached to the bail f, and connected at its other end to a suitable 50 lever arranged upon the upper end of the car,

whereby the cars may be uncoupled from such point.

In operation the opposite car, which is equipped with a similar draw-head and coupling latch or hook, is drawn forward into engagement with the draw-head of the adjacent car, and the hooked ends of the hooks or latches engage the ends of the slots of the draw-heads, and are held in engagement therewith. To uncouple the cars, it is only necessary to operate one of the levers, which raises the coupling hook to which it is attached, and said coupling hook bears against the under side of the hook of the adjacent car and raises 65 the same from engagement.

It will be seen that a car-coupling constructed in accordance with my invention is simple in its construction, yet thoroughly effective and positive in its operation. It will be further seen that there are no springs to become broken or out of order, and that a free movement is allowed in turning curves, thus obviating any liability to breakage.

Having fully described my invention, what 75 I claim as new, and desire to secure by Letters Patent, is—

1. In a car-coupling, the combination, with a draw-head having an opening to receive a portion of the opposite draw-head, of a coupling hook or latch pivoted therein, and consisting of a body portion having an arm or arms provided with a hook or hooks, substantially as set forth.

2. In a car-coupling, the combination, with 85 a draw-head divided into an upper and lower portion, as shown, and having a longitudinal opening, as shown, of a coupling-hook pivoted in said opening, said coupling-hook consisting of a body portion having two forwardly-extending arms provided with hooks, substantially as set forth.

3. The combination, with a draw-head divided into an upper and lower portion, as shown, having their forward ends beveled on 95 their upper and lower sides, and having a longitudinal opening, as shown, of a coupling-hook pivoted in said opening, said coupling-hook consisting of a body portion having two forwardly-extending arms provided with hooks, substantially as set forth.

4. The combination, with a draw-head di-

vided into an upper and lower portion, as shown, having their forward ends beveled on their upper and lower sides, and having a longitudinal opening, of a coupling-hook pivoted in said opening, said coupling-hook consisting of a body portion having two forwardly-extending arms provided with hooks, and a double lever pivotally secured to said hook, substantially as set forth.

In testimony that I claim the foregoing as my own I have hereto affixed my signature in presence of two witnesses.

HERBERT M. STURGIS.
